UNITED STATES PATENT OFFICE.

LEWIS ALLSTON GREELEY, OF MORENCI, MICHIGAN.

IMPLEMENT FOR WEAVING FILLER-WIRES IN WIRE FENCES.

SPECIFICATION forming part of Letters Patent No. 519,154, dated May 1, 1894.

Application filed January 23, 1894. Serial No. 497,764. (No model.)

To all whom it may concern:

Be it known that I, LEWIS ALLSTON GREELEY, a citizen of the United States, residing at Morenci, in the county of Lenawee and 5 State of Michigan, have invented certain new and useful Improvements in Implements for Weaving Filler-Wires in Wire Fences, of which the following is a specification.

The object of this invention is to provide 10 an implement for weaving wire fences or applying filling wires to the longitudinal wires while the latter are on the fence posts, and at the same time to devise an implement or tool which will successfully handle either 15 light or heavy wire and will allow both the longitudinal and filling wires to be spaced as far apart or as near together as desired, so that either a heavy stock fence, or a light poultry fence, may be made with equal facility.

20 This invention consists in combining a bar, a pin or spool supported in such relation to said bar as will leave a space between it and the bar and adapted to receive and hold a coil of wire; and a post connecting the bar and 25 said pin, as will be hereinafter fully set forth.

The invention is illustrated in the accompanying drawings, in which—

Figure 1 is a bottom plan view of the weaving tool or implement. Fig. 2 is a side view 30 of the same. Fig. 3 is an end view. Fig. 4 is a view of one of the coils of wire. Fig. 5 is a plan view of the weaving tool with a coil of wire in position on it. Fig. 6 shows a modification of the tool. Fig. 7 is a view showing 35 the longitudinal wires stretched on the fence posts. Fig. 8 shows on a larger scale the manner of applying the weaving tool to the longitudinal wires when commencing to put on the filler wires. Fig. 9 shows the next step and 40 illustrates a filler wire attached to the two uppermost longitudinal wires. Fig. 10 is a view showing the filler wires fully applied as they are on the finished fence.

In making fences of this character the posts, 45 A, are first set up and then the longitudinal wires, b, are stretched and attached in any preferred way to the posts; these wires may be spread apart any desired distance. The next step is to apply the "filling" or vertical 50 wires, and my invention has reference to this latter operation.

By my invention each of the filling wires of

proper length to reach from the top to the bottom of the fence are first formed into a coil, as seen in Fig. 4, by being wound on a mandrel. This preliminary preparation of the wire is necessary to the use of my tool, which 55 will now be described.

The letter, C, designates a bar, handle, or lever, for convenience I will term it a bar; 60 this bar is made of steel hardened and preferably is provided with a suitable guide for the filler wire. A post, d, of suitable construction is firmly attached to the bar, and a pin, E, to hold a coil of wire is supported by 65 this post near the bar. In the present instance the post, d, has an oblique foot-piece, d', which is at a right-angle with respect to the post; the foot-piece is securely riveted to the bar, C. The pin or spool, E, extends laterally from the post, and in a transverse direction or a direction at right angles with respect to the bar C—in the present instance being rigidly held or supported from the post by one end, as plainly shown in Fig. 3. The 70 pin or spool, E, has such relation to the bar, C, as to have a space, g, between the two (see Fig. 3) in order that a coiled wire may be slipped on the projecting end of the pin or spool. This pin, or spool, is cylindric and 75 fixed so that a coil of filler wire placed loosely on it will revolve readily and thereby unwind. The guide for the filler wire as it uncoils is located in the bar in a direct vertical line under the pin or spool and may comprise a notch, e, formed in the edge of the bar, or, instead of the notch, a hole, indicated by 80 a broken line circle, e', may be made through the bar. The parts may be arranged and constructed to dispense with the guide, it being 85 simply necessary that in drawing the wire from the coil on the pin or spool, E, said wire shall pass by the edge of the bar. The bar may, if desired, and preferably will, be provided with notches, f, f', on its edge, for 90 a purpose hereinafter described.

A coiled filler wire, H, is shown separately 95 in Fig. 4, and is shown mounted on the pin, E, in readiness for use, in Fig. 5.

In order to place the filler wires in a true 100 vertical line a spacer-board, I, is employed; this spacer has loose staples, j, through which the strands or wires, b, pass; the spacer-board has a perpendicular position on these wires

and may be shifted or slid along them and keeps the wires, *b*, at proper distances apart.

The manner of using the tool may be stated as follows: On one end of the coiled filler wire 5 a hook, *k*, is formed by any convenient means, and either before the said coil is placed on the pin or spool, *E*, or after it has been so placed thereon. The spacer-board, *I*, must be slid along the strands or wires, *b*, to the 10 place where it is desired to weave in the first filler wire, *H'*; the tool, with a coil of wire in position on the pin, *E*, is then taken in the hand with the bar, *C*, uppermost, or in position above the pin and coil, and the hook, *k*, on 15 the end of the coil is placed or engaged over the topmost strand, *b*, as shown in Fig. 8. That edge of the bar, *C*, across which the filler wire passes as it uncoils, must be kept next to the spacer-board. The operator will now thrust 20 one of his arms between the strands, *b*, so that each of his hands may grasp an opposite end of the bar, *C*, and then press the tool straight down alongside of the spacer-board until the bar touches the second strand or the one next 25 to the top; the coil, *H*, will unwind by revolving on the pin, *E*. The weaving tool will now be drawn or swung away from the second strand to allow one end of the bar to be thrust under this strand far enough to bring the filler 30 wire in contact with said strand, and then using the bar, *C*, in the manner of a lever the tool will be revolved about the strand to cause the filler wire to make one or more winds, *l*, around it, see Fig. 9. In this figure only one 35 wind, *l*, is shown, but two or three winds may be made if preferred. In this operation of revolving the tool about the strand, in cases where the tool has a guide notch, care should be taken to keep the filler wire in the guide 40 notch, as thereby the wind, *l*, will be drawn tight and the tool will be steadied. When pressing the tool straight down from one strand to another the power that is required to uncoil the wire, together with the friction 45 produced by turning the coil on the fixed or rigid pin, *E*, straightens out the convolutions of the coiled wire. When using the bar, *C*, as a lever to revolve the tool about one of the 50 strands, *b*, for the purpose of winding the filler wire around the strand, the friction re-

ferred to affords sufficient tension to insure that the wind, *l*, will be tight. After the wind, *l*, has been made about the second strand, as described, the tool will then be pressed straight down alongside of the spacer-board 55 to the third strand which also will be wound as the second strand was; this operation will be repeated to the fourth or lowermost strand. To finish the filler wire the hook, *k*, at the topmost strand should be fastened or wound 60 about the strand; this can be done by simply grasping the end of the hook in one of the notches, *f*, *f'*, in the bar and revolving the tool as before. These notches are of different sizes to suit larger or smaller wires. Having 65 finished the application of one filler wire, the next step is to slide the spacer-board along the strands, *b*, to the point where the next filler wire is to be applied, and then the operation already described is repeated. 70

In the modification, Fig. 6, the post, *d'*, is formed integral with the bar, by simply bending the end of the bar and giving it a quarter twist.

Having thus described my invention, what 75 I claim as new, and desire to secure by Letters Patent, is—

1. A hand-operated tool for weaving the 80 filler wires in wire fences, comprising a lever-bar; a pin for holding a wire-coil and extending in a transverse direction with respect to the lever-bar and supported so as to leave a space between it and the bar; and a post connecting the bar and one end of said pin.

2. A hand-operated tool for weaving the 85 filler wires in wire fences, comprising a lever-bar; a pin for supporting a wire-coil and extending in a direction transversely with respect to the lever-bar and supported so as to leave a space between it and said bar; a post 90 connecting the lever-bar and one end of said pin; and a guide in the lever-bar in a direct vertical line below the said pin, substantially as described.

In testimony whereof I affix my signature in 95 the presence of two witnesses.

LEWIS ALLSTON GREELEY.
